UNITED STATES PATENT OFFICE

KARL SCHREER, OF ERLANGEN, NEAR NUERMBERG, GERMANY, ASSIGNOR TO M. E. BERNHARDT COMPANY, INC., OF NEW YORK, N. Y., A CORPORATION OF NEW YORK

LIGHTER

Application filed August 4, 1928, Serial No. 297,479, and in Germany August 29, 1927.

This invention relates to lighters and more specifically to what are commonly known as cigar and cigarette lighters, the primary object of the invention being to provide a device of this character in which the lighter mechanism is movable relatively to a container so as to either enclose the lighter mechanism or project it from the container in position for use.

10 A further object is to provide a device of this character which will be of neat and attractive appearance and which will most efficiently perform the functions for which it is intended.

15 With these and other objects in view, the invention consists in certain novel features of construction and combinations and arrangements of parts, which will be more fully hereinafter described and pointed out 20 in the claims.

In the accompanying drawings—

Figure 1 is a perspective view of my improved lighter in closed inoperative position;

25 Figure 2 is a similar view showing the lighter in open or projected operative position;

Figure 3 is a view in section longitudinally of the casing when the lighter mechanism is 30 withdrawn and enclosed;

Figure 4 is a view similar to Figure 3 showing the lighter mechanism projected and in operative position;

Figure 5 illustrates the casing in section 35 with the lighter mechanism removed and in elevation;

Figure 6 is a view in section on the line 6—6 of Figure 3.

1 represents the outer or enclosure casing 40 of my improved device, and this outer casing includes a pair of disks having inwardly turned meeting flanges 2, 2 secured together in any approved manner. These flanges 2, 2 are cut away forming an opening 3 and a slot 45 4 communicating therewith for a purpose which will hereinafter appear.

A disk 5 is mounted to turn within the casing 1 and is of approximately the same diameter as the casing 1. This disk 5 has a 50 laterally projecting flange 6 at its edge with

an opening 7 provided in the flange of a length corresponding to the combined length of the opening 3 and slot 4 in casing 1.

Within the casing 1 a lighter mechanism is adapted to be housed and this lighter mechanism includes a reservoir 8 for benzine or other liquid fuel and a packing such as is commonly employed in the art.

The reservoir 8 has a tube 9 fixed therein with a check valve 10 at its lower end. This tube 9 is adapted to support a removable post 11 bifurcated at its upper outer end and in which bifurcated end a toothed wheel 12 is mounted which engages a block 13 of pyrophoric alloy or other sparking material located within the hollow post 9.

In this post 9 a spring 14 is provided, exerting pressure on the block 13, and a set screw 15 is provided in the end of the post to regulate the pressure of the spring and consequent frictional engagement of the sparking block 13 against the wheel 12.

A wick tube 17 projects through the wall of reservoir 8 adjacent the wheel 12 and supports a wick 18 which extends into the reservoir.

The hollow or tubular post 11 and the tube 9 are so shaped as to prevent any turning movement of the post in the tube. This may be accomplished simply by flattening one wall of the post and tube, as illustrated clearly in Figure 6.

To fill or charge the reservoir with benzine or other liquid it is simply necessary to draw the post 11 out of the tube 9 and pour the liquid through the tube past the check valve 10.

The reservoir 8 with this arrangement of sparking wheel 12 and wick 18 constitutes what may be termed the sparking mechanism per se as it is to be understood of course that the turning movement of the wheel 12 will cause the sparks to ignite the wick as is done in the ordinary manner.

The disk 5 above referred to is made with concentric slots 19 and 20 through which pins 21 and 22, respectively, on one of the outer casing members 1 project. The reservoir 8 at one side has an opening 23 therein re-

ceiving the pin 22 so as to freely pivot on said pin.

The disk 5 is made with a somewhat radially positioned slot 24 receiving a pin 25 on the reservoir 8 at a point removed from the pivot pin 22. A knob 26 is secured to the flange 6 of disk 5 and has a reduced shank portion movable in the slot 4 of the outer casing 1.

10 The operation of my improved device is as follows:

Normally the parts are as shown in Figures 1 and 2, that is, with the lighter mechanism wholly enclosed in the casing 1 and the knob 26 moved to one extreme position, as illustrated in the drawing. To move the lighter mechanism to operative position the knob 26 is moved to the right of Figures 1 and 3, causing the disk 5 to turn. This movement 20 of the disk 5 by reason of the engagement of pin 25 with the slot 24 in the disk 5 will cause the lighter mechanism to move upwardly and outwardly, as indicated in Figures 2 and 4, said lighter mechanism pivoting on 25 the pin 22. This movement of the knob 26 also in turning the disk 5 brings the opening 7 in the flange 6 of said disk into register with the opening 3 so that an opening or space is provided through which the wheel 12 and the 30 wick 18 are projected, and positioned for operation. When the knob 26 is moved in the opposite direction the lighter mechanism as a whole will move inwardly and downwardly and be completely enclosed as above 35 stated.

While I have illustrated what I believe to be a preferred embodiment of my invention, it is obvious various changes and alterations might be made in the general form of 40 the parts described without departing from my invention and hence I do not limit myself to the precise details set forth but consider myself at liberty to make such changes and alterations as fairly fall within the spirit 45 and scope of the appended claims.

I claim:

1. A device of the character described, including an outer casing having an opening in its wall, a disk mounted to turn in the casing 50 and having an opening therein adapted to register with the opening in the wall of the casing, means for imparting a turning movement to the disk, a lighter mechanism normally enclosed in the casing and having 55 pivotal mounting at one portion and having a pin remote from said pivotal portion, said disk having a slot therein receiving the pin whereby a pivotal movement is imparted to the lighter mechanism when the disk is turned 60 so as to project the sparking mechanism of the lighter mechanism through said opening into the casing and into operative position.

2. A device of the character described including a casing having an opening in its

wall, a flanged disk mounted in the casing, having an opening in the flange adapted to register with the opening in the casing, a knob secured to said flange adapted to turn the same by manual manipulation, said disk 70 having opposed concentric slots therein, pins on the casing projecting into said slots, a lighter mechanism including a reservoir pivotally connected to one of said pins, a slot and pin connection between said reservoir and the disk whereby the turning movement of the disk causes the reservoir to be moved toward and away from said opening, a sparking wheel carried by the reservoir, sparking material carried by the reservoir in engagement with the wheel, and a wick carrier adjacent the wheel, said sparking wheel and wick carrier being movable through said opening when the disk is turned in one direction and moved into and enclosed in the 85 casing when the disk is moved in the opposite direction.

3. A device of the character described, including an outer casing, having an opening in its wall, a lighter mechanism movably mounted in the casing, a member normally closing the opening in the casing, said member operatively connected to the lighter mechanism whereby when the member is moved to uncover the opening in the casing 90 the lighter mechanism will be projected through the opening.

4. A device of the character described, including an outer casing, having an opening in its wall, a lighter mechanism movably mounted in the casing, a member normally closing the opening in the casing, said member operatively connected to the lighter mechanism whereby when the member is moved to uncover the opening in the casing 105 the lighter mechanism will be projected through the opening, said lighter mechanism having an eccentric mounting within the casing and having a partial turning movement imparted by the said member.

KARL SCHREER.
